UNITED STATES PATENT OFFICE.

HENRY A. HILDRETH, OF AUBURN, MAINE.

SHOE-TAG HOLDER.

SPECIFICATION forming part of Letters Patent No. 680,975, dated August 20, 1901.

Application filed January 15, 1900. Serial No. 1,415. (No model.)

To all whom it may concern:

Be it known that I, HENRY A. HILDRETH, a citizen of the United States, residing at Auburn, in the county of Androscoggin and State 5 of Maine, have invented certain new and useful Improvements in Shoe-Tag Holders; and I do hereby declare the following to be a full, clear, and exact description of the invention, such as will enable others skilled in the art to 10 which it appertains to make and use the same.

The present invention relates to shoe-tag holders, and has for its object to provide a device which may be easily attached to a shoe-sole and which shall securely hold and retain 15 a tag inserted therein.

To the above end the invention consists in the combinations hereinafter described, and more particularly set forth in the claim.

Heretofore it has been customary for sales- 20 men to identify their different samples of boots and shoes by means of paper tags attached to the boot strap or pull. This practice is objectionable, however, in that the tag must be held in the hand in order to be read, 25 that it is easily soiled by contact with the shoe and the constant handling necessary, and that it is often accidentally detached. In the present invention all these objectionable features are absent, the tag being held securely on the 30 shank portion of the sole, where it may be easily read by simply turning the shoe bottom side up and where it is protected from contact with the shoe and all danger of soiling consequently avoided.

35 In the illustrated embodiment of my invention, Figure 1 is a perspective view of the improved shoe-tag holder attached to a shoe and holding a tag. Fig. 2 is an enlarged view of the tag-holder.

40 My device is preferably constructed from a single piece of spring-wire and is bent to assume the shape hereinafter described. At each end of a wire of suitable length are formed jaws or clips, which preferably consist 45 of the portions 1 and 2, adapted to engage the edge and top of the sole 3, respectively. The end 4 of the top-engaging portion 2 is preferably bent backward against itself in order to avoid the danger of cutting or scratch- 50 ing the upper with the end of the wire. Approximately midway between each jaw and the middle of the length of wire are formed

the loops 5, which not only allow the laterally-springing movement of the jaws, but also coöperate in holding the tag in position. The middle portion 6 is preferably provided with a projection 7, formed by a V-shaped bend in the wire at right angles to the plane of the loops 5. The object of this projection 7 is to press the tag against the sole 3 to hold it securely in proper position.

In the operation of my device the jaws are sprung apart by the fingers or any suitable means, so that the top-engaging portion 2 may pass over the edge of the sole. Upon 65 releasing the jaws they will engage the sole on its edge and top and hold the device against the shank. A card or tag 8 may then be easily inserted under the portion 6 and pushed back against the bottom of the loops 5, where it 70 will be held by the spring of the loops as well as by the pressure of the V-shaped projection 7. If desirable, the tag may be inserted in the holder before the latter is attached to the shoe.

I am aware that tag or ticket holders have been constructed in which the tag and article to be marked are both held between the same spring jaws or clips, while a backing-plate for the tag is held by edge-gripping jaws. These 80 devices, however, differ essentially from mine in that they grip both the tag and article to be marked between the same spring clips or jaws—a method of attachment obviously not adapted to shoe-soles. So far as I am aware 85 I am the first to combine with means adapted to hold a shoe-tag in a plane parallel to the sole spring attaching jaws or clips adapted to engage the edge and top of the sole.

Having thus described my invention, I claim as new and desire to secure by Letters Patent of the United States—

A shoe-tag holder, comprising spring-clips to engage the projecting edge of a shoe-sole and a tag-holder secured to the edge clips having spring tag-holding loops to grip and hold a shoe-tag, substantially as described.

In testimony whereof I affix my signature in presence of two witnesses.

HENRY A. HILDRETH.
